US00D585023S

(12) **United States Design Patent**
Münch et al.

(10) **Patent No.:** US D585,023 S
(45) **Date of Patent:** ** Jan. 20, 2009

(54) **SIMPLE C-CONNECTOR**

(75) Inventors: **Markus Münch**, Coswig (DE); **Florian Zschoge**, Dresden (DE)

(73) Assignee: **Solarwatt AG**, Dresden (DE)

(**) Term: **14 Years**

(21) Appl. No.: **29/293,441**

(22) Filed: **Nov. 26, 2007**

(51) **LOC (9) Cl.** 13-03

(52) **U.S. Cl.** D13/133; D13/154

(58) **Field of Classification Search** D13/133, D13/154, 184, 199; 136/244, 256; 439/66, 439/62, 65, 82, 83, 567, 636, 660, 682, 856, 439/857, 862

See application file for complete search history.
